CLAIM

The ornamental design for a cleaning tool, as shown and described.

DESCRIPTION

FIG. 1 is a perspective view of a cleaning tool showing our new design, with a cleaning implement secured to the cleaning tool;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a perspective view of the cleaning tool of FIG. 1, with the cleaning implement removed from the cleaning tool;

FIG. 9 is a front elevation view of FIG. 8;

FIG. 10 is a rear elevation view of FIG. 8;

FIG. 11 is a left side elevation view of FIG. 8;

FIG. 12 is a right side elevation view of FIG. 8;

FIG. 13 is a top plan view of FIG. 8; and,

FIG. 14 is a bottom plan view of FIG. 8.

The broken lines in the drawings depict portions of the cleaning tool that form no part of the claimed design.

1 Claim, 10 Drawing Sheets
